CLAIM

The ornamental design for a connecting terminal, as shown and described.

DESCRIPTION

FIG. 1 is a bottom plan view of a connecting terminal, showing our new design.

FIG. 2 is a front elevation view thereof.

FIG. 3 is a rear elevation view thereof.

FIG. 4 is a top plan view thereof.

FIG. 5 is a right side elevation view, the left side elevation view being a mirror image thereof.

FIG. 6 is a top, rear, left side perspective view thereof; and, FIG. 7 is a top, rear, left side perspective view of the connecting terminal of FIG. 1, shown in a condition of use. The broken lines in the drawings depict environmental structure that form no part of the claimed design.
